UNITED STATES PATENT OFFICE.

WALTER E. DUNCANSON, OF NEW YORK, N. Y., ASSIGNEE TO THE J. G. WILSON CORPORATION, OF NEW YORK, N. Y., A CORPORATION OF VIRGINIA.

BLIND OR AWNING CONSTRUCTION.

Application filed September 14, 1925. Serial No. 56,109.

This invention relates to new and useful improvements in blinds and it pertains more particularly to a blind which is adapted for use on the exterior of a door or window opening and is in the nature of an awning.

An awning as commonly constructed, comprises a canvas hood like structure supported over the upper portion of a door or window opening and adapted to be lowered to partially close the door or window opening. This type of awning while effective in shutting off strong lights, also has the disadvantage of cutting off too much of the light. Furthermore an awning of this character interferes to a great extent with the ventilation through the door or window opening when the awning is lowered and also in many cases when the awning is in its raised position.

20 Awnings have been produced comprising a series of parallel slats secured together to form a slat structure and arranged to be applied to a door or window with the lower part of the slat structure spaced from the door or window so that the slat structure extends at an angle from the upper portion of the door or window opening.

As far as applicant is aware, awnings of this type have not been provided with adjustments for varying the passage of light or air through the same. Also in such prior awning structures, the lower part of the awning is located in spaced relation to the window by a manual operation independent of the raising and lowering operation.

It is one of the objects of the present invention therefore to provide an improved awning construction by which both the volume and degree of light and ventilation are 40 at all times under control and may be varied at will.

Another important object of the invention is to provide an improved awning of the Venetian blind type in which the lower part 45 of the awning will be located in spaced relation to the door or window automatically during the lowering operation to locate the awning in an inclined position.

Another object of the invention is to provide an improved awning construction of the Venetian blind type in which the awning may be located in an inclined position with relation to the door or window or in substantially parallel relation thereto as desired.

With these and other objects in view, the invention comprises certain novel and improved features, construction and combinations of parts hereinafter described and particularly pointed out in the claims, the advantages of which will be readily understood and appreciated by those skilled in the art.

The invention will be clearly understood from the accompanying drawings illustrating the invention in its preferred form, and the following detailed description of the constructions therein shown.

Referring to the drawings,

Figure 1 is a perspective view of a window showing a blind or awning constructed in accordance with the present invention in place thereon, the blind or awning being partially extended;

Figure 2 is a view in front elevation of the blind or awning showing the same in its 75 fully extended position;

Figure 3 is a longitudinal sectional view taken on the line 3—3 of Figure 2;

Figure 4 is a view in front elevation showing the blind in completely folded position; 80

Figure 5 is a detail longitudinal sectional view taken on the line 5—5 of Figure 4;

Figure 6 is a view in end elevation showing the upper portion of the blind or awning; and

Figure 7 is a top plan view of the upper portion of the blind or awning.

In the accompanying drawings, the reference numeral 10 designates a window, the frame and sill thereof being designated by 85 the reference numerals 11 and 12 respectively.

The blind or awning is, generally speaking, of the "Venetian" type and comprises a plurality of slats 13, secured between tapes 95 14 in such a manner that when the blind or awning is extended the slats will occupy positions in which they are spaced with respect to each other, or when the blind is folded, the several slats occupy positions in 100 contact with each other. In addition to the foregoing, the slats 13 when the blind or awning is extended may be rocked or angularly disposed between the tapes in order to vary the degree of light and air admitted 105 therethrough.

The tapes 14 between which the several slats are mounted and which serve to support said slats are connected at their upper ends to a transversely extending tilting bar 15 110

which bar extends across the upper portion of the window frame 11.

To adjust the several slats in different angular positions this bar is rocked about a horizontal or longitudinal axis, and to provide for rocking movement of this bar 15 each of its ends is provided with a pivot pin 16, which pins 16 engage in openings in brackets 17 and 18.

10 A transversely extending bar 16' is rigidly supported upon brackets 20', and this bar 16' is provided with a longitudinally extending slot or elongated recess which extends from a point adjacent one of its ends through 15 the remainder of its length in the direction of the opposite end, and mounted in said slot or recess there are three pulleys 19, 20 and 21. This slot or recess is covered by a plate 15' when the several parts are in fully assembled positions.

Passing over the pulley 19 there is a cord 23, and this cord 23 is attached at its lower end to the lowermost slat 24 of the blind or awning nearer one end thereof and extends 15 upwardly through openings 25 in the several slats 13, these slats 13 being provided with the openings 25 near each end.

Connected at its lower end to the lowermost slat 24 of the blind at a point nearer 30 the end thereof opposite that to which the cord 23 is attached, there is a cord 26, and this cord 26 passes upwardly through openings 25 in the slats 13 and over the pulley 20. Both of these cords 23 and 26 pass over 35 the pulley 21, and one of said cords extends downwardly preferably to a point adjacent the base of the window or door opening where it may be conveniently grasped, the other cord being attached to the latter cord 40 as at 27 (see Figure 2). By exerting a pull upon that cord which is extended toward the base of the door or window opening, the lowermost slat 24 will be raised, and the several slats will be brought with their flat 45 sides in contact with each other to the position shown in either Figure 1 or Figure 5, depending, of course, upon the extent of movement imparted to the extended cord.

As heretofore stated, the transversely-extending bar 15 is adapted for rocking movement about its longitudinal axis, and this movement is produced by means of a looped cord, the two ends of which are connected to the forward edge of the transversely-extending bar 15, as at 30. One part 50 of this looped cord, passes from its point of attachment to the bar 15, over said bar and then downwardly while the other part 55 of the cord passes under the bar 15, then over a pulley 29 carried by the bracket 17 and then downwardly. This construction and arrangement of parts permits of rocking the bar 15 in either direction from a horizontal position approximately one-quarter 60 of a revolution to tilt the slats 13 by pulling

respectively upon the parts 27 and 28 of the cord, the direction of movement depending upon which part of the cord is pulled.

The bracket 17 comprises a base portion 31, a depending end portion 32, (see Fig. 4) 70 which pivotally supports one end of the bar 15, said end portion 32 being provided with an opening 34 for the reception of the pin 16 on the end of the bar. The bracket is also formed with depending projections 33 and 35, between which the pulley 29 is mounted. The projections 33 and 35 are located to the rear of the bar 15 as more clearly shown in Figs. 3 and 6 so as to locate the pulley 29 in the proper operating position with relation to the bar 15 and so as not to interfere with the tilting of said bar.

The bracket 18 heretofore mentioned which supports the other end of the transversely-extending bar 15 comprises a base portion 36 and a depending portion 37 which latter is provided with an opening for the reception of the pin 16 carried by the other end of the bar 15.

These two brackets 17 and 18 are preferably secured to the under side of the transversely-extending bar 16', thereby suspending the tilting bar and slats from said bar 16'.

In the present awning or blind construction, devices are provided for controlling the 95 position of the lower part of the blind, which upon lowering the blind from its upper position at the top of the window opening to predetermined points in said window opening will automatically operate to space the 100 lower part of the blind at predetermined distances from the window as shown in Fig. 1 to locate the blind in an inclined position. Upon lowering the blind still further, these devices will cause the lower part of the 105 blind automatically to swing in toward the window frame until when the blind is in its lowermost position, it will lie substantially parallel with the window frame as shown in Fig. 3.

The devices for controlling the position of the lower portion of the blind in the manner above described comprise two supports, one located on each side of the blind. Inasmuch as these supports are of substantially the 115 same construction, a description of one will suffice for both.

These supports comprise a rod 42 pivotally engaged in openings in projections on a bracket 40. This rod comprises a part 43 which is bent at an angle to that part of the rod which engages in bracket 40 to offset the body of the rod from the blind as shown in Fig. 3. The body of the rod 42 is bent at an angle to a portion 43 so that when 120 the rod is in a certain position, the body portion may extend in a direction very nearly parallel to the plane of the blind.

The body portion of the rod 42 is slidably engaged in a tubular member 45 pivoted at 130

46 upon the door or window frame. Thus rod 42 can telescope within tubular member 45 and the part 43 of the rod forms a stop limiting this telescoping movement.

With the above construction, when the blind is raised to its uppermost position, the parts of the devices for controlling the position of the lower part of the blind will assume substantially the positions shown in Fig. 5. In lowering the blind, the cords 23 and 26 are slackened off and the blind will descend under the action of gravity. As the blind descends, the rods 42 will telescope within the tubular members 45 until parts 43 of the rods engage the ends of the tubular members, the blind descending substantially parallel with the window frame during this part of its downward movement. When the telescoping of the rods 42 within the tubular members has thus been arrested, upon further downward movement of the blind, the rods 42 and members 45 will swing outwardly about pivots 46 and the lower part of the blind thereby will be caused to swing outwardly away from the window frame into an inclined position, as shown in Fig. 1. When in this position, the blind forms an inclined awning over the window and its slats may be adjusted in any desired inclined position for the purpose of admitting or excluding air or light.

If it is desired to allow the blind to descend until it covers completely the window opening, the cords 23 and 26 are further slackened off, allowing the lower part of the blind to descend still further. During this further downward movement, the tubular members 45 and rods 42 will swing inwardly about the pivot 46, thereby causing the lower part of the blind to swing inwardly, until when the blind has descended to its lowermost position, it will be located substantially parallel to the window as shown in Fig. 3.

With the above construction the tilting bar 15 may be tilted by pulling upon the portions 27 or 28 of the tilting cord whether

the awning is located in an inclined position with relation to the door or window or whether the awning is located substantially parallel thereto. Thus the angular positions 50 of the slats may be adjusted to regulate the admission of light and air with the awning in any of its various positions.

The awning may be located in various inclined positions with relation to the door 55 or window by stopping the descent thereof at various points after the lower part of the awning starts to swing out away from the window in the manner described above. It will be understood, of course, that the blind 60 or awning is maintained in its adjusted position by securing the cords 23 and 26 by which it is operated.

It is to be understood that the invention is not limited to the particular construction 65 and arrangement of parts of the illustrated embodiment of the invention but that the invention may be embodied in other forms within the scope of the claim.

Having explained the nature and object 70 of the invention and having specifically described a construction embodying the invention in its preferred form, what is claimed is:

In a blind and awning construction comprising a series of parallel slats, means for supporting said slats adjacent a door or window opening, and means for raising and lowering the blind, a swinging support for the lower end of the blind made up of two 80 or more parts telescopically connected and a stop to limit the telescoping movement of said parts so that in raising or lowering the blind, the blind is first moved substantially parallel with the window, is then swung 85 out into an inclined position, and then inwardly toward the window, and is again moved vertically substantially parallel with the window.

Signed at New York, N. Y. this 20th day 90 of August 1925.

WALTER E. DUNCANSON.
